TARGET PAINTING DEVICE

Clarence R. Shultz, Independence, Kans.

Application June 3, 1938, Serial No. 211,663

6 Claims. (Cl. 91—41)

This invention relating as indicated to a target painting device is more particularly directed to a means for painting targets as well as the surface surrounding said target so that such surface and the target will always present a neat and sightly appearance.

In target games the target itself as well as the surrounding surface usually presents an unsightly appearance due to the impact of bullets, the net result of which is that the game apparatus, or other device, in which the target is incorporated is not attractive and fails to draw customers. I have cured this difficulty by providing one or more brushes, which normally rest in a paint or coating composition receptacle and means for elevating said brushes and imparting an oscillatory movement thereto which closely simulates hand brushing.

It is also an object of the invention to provide a control adjacent the shooter in the form of a push button or similar device which will start the apparatus in motion by merely pressing such button and such apparatus will continue to function until the target surrounding the surface has been thoroughly covered with the coating composition.

In the description hereafter I will refer to the coating composition as paint but it is to be understood that I am not to be restricted to any particular substance, as paint, lacquer, or any equivalent material may be used with equal facility.

To the accomplishment of the foregoing and related ends, said invention, then, consists of the means hereinafter fully described and particularly pointed out in the claims; the annexed drawings and the following description setting forth in detail certain structure embodying the invention, such disclosed structure constituting, however, but one of various structural forms in which the principle of the invention may be used.

In the accompanying drawings:

Fig. 1 is a vertical section taken on the line 1—1 of Fig. 2.

Fig. 2 is a transverse vertical section taken on line 2—2 of Fig. 1.

Fig. 3 is a detail view of the clutch with parts in section.

Fig. 4 is a detail elevation of the means for imparting oscillatory movement to the brushes.

Fig. 5 is a detail end elevation of the painting receptacle.

Fig. 6 is a wiring diagram.

Fig. 7 is a detail elevation of the switch 65.

Referring now to the drawings, and more particularly to Figs. 1 and 2, it will be seen that I

have provided a cabinet 1 which has in its front face an opening 2 through which missiles are adapted to be projected. This cabinet has an interior partition 5 upon which a target 3 is supported and such target is surrounded by a surface 4, it being my intention to provide means to maintain such target and surface clean and neat appearing at all times. The means for doing this comprises a motor 6, brushes 21 and 22 and the mechanism associated therewith. A belt 7 extends from a pulley on the motor shaft to pulley 8 on the driven shaft 9. This driven shaft has supported thereon at opposite ends, pulleys 10 and 11 which are freely supported upon the shaft 9 but have associated therewith compression 15 springs 12 and 13 which form a pair of slip clutches. Cables 14 and 17 extend over pulleys 15 and 18 respectively, and are secured at one end to T's 16 and 19, respectively. It will be noted that I have used T's for this purpose but any 20 other form of fitting may be employed. A cross bar 20 is rotatably supported in the T's 16 and 19 and brushes 21 and 22 are rigidly attached to such cross bar. A vertically disposed pair of T's 23 and 24 are attached to the T's 19 and 16, 25 respectively and also to the rods 25 and 26 which are telescoped within the tubes 25a and 26a (see Fig. 1). A second cross bar 22a extends between the vertically disposed T's 23 and 24 and this cross bar does not rotate as is the case with 30 the bar 20.

From the preceding description it is obvious that when the motor is started belt 7 rotates pulley 8 which in turn drives shaft 9 and pulleys 10 and 11, which wind up cables 14 and 17, which 35 in turn elevate cross bars 20 and 22a, and brushes 21 and 22. In this manner the cross bars, brushes, T's 19, 16, 23 and 24 and rods 25 and 26, are elevated as a unit.

In order to maintain the brushes 21 and 22 40 in a substantially vertical position as they rise, a guide member 27 is provided with a vertical slot 28 therein for the reception of the right hand end (as viewed in Fig. 1) of rod 20. The rod 20 at such end has a transverse pin 29 therein so that 45 regardless of the position of the brushes when they are elevated they will assume a vertical position as they descend into the paint receptacle. This is due to the fact that pin 29 extends upwardly from rod 20 and the sides of guide 27 50 cause pin 29 to assume a vertical position as it descends.

In order to secure a brushing action I have provided a cam 33, which is fixed upon the shaft 9. This cam engages a lever 32 pivoted at 32a 55

and a cable 31 extends from one end of lever 32 and wraps around pulley 30, which is fixed to shaft 20. A spring 49 is adapted to connect pulley 30 with the bracket 48. Thus it will be seen that when the rod 20 assumes the dotted line position shown in Fig. 1, the cable 31 becomes taut, whereupon the cam 33 forces the lever 32 downwardly and this pulls the brushes 31 and 32 from a vertical to a horizontal position and finally to an upwardly extending position. In this manner the brushes are caused to move in an arc, much in the manner of manual painting. After the brushes have reached their upper line of movement, as shown in dotted lines in Fig. 1, the spring 49 functions to return the pulley 30 back to its normal rotary position as distinguished from its normal vertical position and thus the brushes go through the same arc in reverse direction.

20 The pins 50 and 51 stop cross bar 20 in a position just above the targets 3 and 3a and altho the motor 6 is still running the pulleys 10 and 11 are not rotated due to the slip clutch arrangement, and this holds the paint brushes in position over the targets. At the same time the cam 33 on shaft 9 rides on pedal 32 which alternately tightens and loosens the cable 31. With each rotation of the cam 33 the pedal or lever is pushed down and thus the cable 31 exerts a pull on pulley 30, which in turn moves cross bar 20 causing the paint brushes to turn up against the metal plate 4. When the high side of cam 33 contacts lever 32 spring 49 is placed under tension and when the low side contacts the lever the spring 49 returns the pulley 30 to its normal position and in doing so returns the paint brushes to a vertical position. This oscillating movement is preferably repeated four times by means of a device which I will now describe.

40 A slip clutch, shown in detail in Fig. 3, is mounted on shaft 9. The pulley 8 is loosely mounted on such shaft and has an extended hub 42 with a recess therein adapted to receive the sliding collar 40. The sliding collar 40 contains a pair of axial slots and a pin 41 fixed to shaft 9 is received in such axial slots. This permits axial movement of the sliding collar 40 and thus rotation is imparted to shaft 9 when the sliding collar 40 engages the pulley 42 of the hub 8. A fork 14 pivoted at 14 to the partition 5 engages a groove 43a in the collar 40 at one end and at the other abuts cam 44 at all times due to the presence of spring 46. Cam 44 is fixedly mounted upon shaft 45 and this shaft has a star wheel 47 mounted at one end thereof. A pin 48 mounted upon pulley 8 is adapted to engage the serrations on the star wheel so that the clutch member 40 and 42 engage and release at predetermined times. Each time the shaft 9 rotates, pin 48 on pulley 8 contacts one tooth on star gear 47 which turns shaft 45 and cam 44 one-tenth of a revolution. When the cam 44 contacts lever 43 it opens the clutch or moves the collar 40 away from hub 42. This permits free action of shaft 9 as the pulley 8 is loosely mounted upon such shaft. When shaft 9 is released the weight of the paint brush assembly is more than sufficient to unwind cables 14 and 17 which allows the paint brushes to return to the paint receptacle 52 and assume the position shown in Fig. 1. As the cross bar and paint brush assembly descends it is held in proper position by pin 29 engaging the guide member 27. When the cross bar 22a, which is associated with the paint brushes and cross bar 20, reaches its lowermost position (shown in Fig. 1) it forces the

switch blade 62 downwardly, thus breaking the circuit between lines 67 and 68 shown in the wiring diagram (Fig. 7) and stopping motor 6.

Current is supplied through service lines 60 and 61 and when it is desired to start the apparatus it is merely necessary to push the push button 63. This supplies current to the motor and when the cross bar 22a is lifted spring 69 forces switch blade 62 upwardly, thus making the circuit between contact 66 and contact 70, or stated in other words, completing the circuit through lines 61, 67, 68 and 64.

In order to prevent the paint or coating composition from unduly evaporating and at the same time preventing the paint from splashing, due to particles of lead falling in the paint receptacle, I have employed the means shown in Fig. 5 which consists briefly of a spring pulled lever 54 fixed to the lid 53 of the receptacle 52. The weight of the cross bars 20 and 22a is more than sufficient to overcome the force exerted by spring 55 so that as the brushes descend to the position shown in full lines in Fig. 1, the cross bar 22a engages one end of the lever 54, thus closing the lid 53. The cross bars are received in slots 56 and 57 in opposite ends of the receptacle 52. When the cross bars start upwardly the spring 55 pulls lever 54 and opens the lid and maintains it open until the brushes have again descended.

From the foregoing description it will be seen that I have provided a means for painting or coating a target and/or a target surface which functions mechanically and closely simulates manual painting. It will also be noted that it is merely necessary to push a button, whereupon the apparatus is set in motion and a desired number of oscillations may be imparted to one or more brushes. In this connection it is to be observed that the number of brushes is a matter of choice, depending upon the space to be covered and that I may use two brushes or as many more as is desired. It will also be observed that the number of oscillations imparted to the brushes is again a matter of choice as this may be varied by varying the number of serrations in the star gear 47. It will thus be seen that I have provided an automatic apparatus which at the same time is flexible in that it can be easily changed to meet any of a number of various conditions.

Other modes of applying the principle of my invention may be employed instead of the one explained, change being made as regards the means and the steps herein disclosed, provided those stated by any of the following claims or their equivalent be employed.

I therefore particularly point out and distinctly claim as my invention:

1. In apparatus of the character described, the combination of a motor, a shaft driven by said motor, a pulley on said shaft, a cable wound upon said pulley, a cross bar, said cable being attached to said cross bar, and a brush attached to said bar, movement of said driven shaft elevating said cross bar and brush, and means associated with said driven shaft and cross bar for oscillating said brush.

2. In apparatus of the character described, the combination of a motor, a shaft driven by said motor, a pulley on said shaft, a cable wound upon said pulley, a cross bar, said cable being attached to said cross bar, and a brush attached to said bar, movement of said driven shaft elevating said cross bar and brush, and means associated with said driven shaft and cross bar for oscillating said brush, said means comprising a cam mounted

upon said driven shaft, a lever engaging said cam, a cable attached to said lever and to said cross bar and a spring maintaining said cross bar in desired position.

5. 3. In apparatus of the character described, the combination of a brush and means to oscillate said brush, said means including a positively driven element, a pin on said element, a star gear and a clutch between said positively driven element and said brush, said pin by engaging said star gear opening and closing said clutch.

10. 4. Means for painting a target comprising an oscillatable cross bar, a brush fixed to said cross bar, a pair of rods having journals to receive said bar, a second cross bar fixed to said rods, a pair 15 of tubular members adapted to receive said rods and means to reciprocate said cross bars as a unit.

5. Means for painting a target comprising an oscillatable cross bar, a brush fixed to said cross bar, a pair of rods having journals to receive said bar, a second cross bar fixed to said rods, a pair of tubular members adapted to receive said rods and means to reciprocate said cross bars as a unit. 5

6. Means for painting a surface comprising an oscillatable cross bar, a brush fixed to said cross bar, a pair of rods having journals to receive said bar, a second cross bar permanently fixed to said rods, a pair of tubular members adapted to receive said rods, means to elevate said bars a predetermined distance, said second bar being located below said oscillatable cross bar. 10 15
